US0D1113830S

(12) **United States Design Patent** (10) **Patent No.:** **US D1,113,830 S**
Da Costa E Sousa (45) **Date of Patent:** **** Feb. 17, 2026**

(54) **REMOTE CONTROL WITH CLEANABLE COVER**

(71) Applicant: **TECH4HOME, LDA**, São João Da Madeira (PT)

(72) Inventor: **Tiago Jorge Da Costa E Sousa**, Canelas (PT)

(73) Assignee: **TECH4HOME, LDA**, Sao Joao Da Madeira (PT)

(**) Term: **15 Years**

(21) Appl. No.: **29/906,895**

(22) Filed: **Nov. 13, 2023**

(51) **LOC (15) Cl.** **14-03**

(52) **U.S. Cl.**

USPC **D14/218**

(58) **Field of Classification Search**

USPC ..... D14/218, 388, 456, 496, 400, 401; D13/168, 162–164, 171, 173, 174; D21/333; D11/26, 29, 34, 37, 38 CPC .
